UNITED STATES PATENT OFFICE.

CARL M. FOGELQUIST, OF NEW YORK, N. Y.

FOLDING BRACKET FOR CARRIAGE-TOPS.

SPECIFICATION forming part of Letters Patent No. 253,364, dated February 7, 1882.

Application filed September 8, 1881. (No model.)

To all whom it may concern:

Be it known that I, CARL M. FOGELQUIST, of the city of New York, in the county and State of New York, have invented a new and 5 useful Improvement in Folding Brackets for Carriage-Tops, of which the following is a specification.

My invention relates especially to carriages for infants, its object being to provide a simple 10 and conveniently-adjustable brace, by which the carriage-top supported by said brace may be not only felled down behind the body of the carriage, as heretofore, when shade is not needed, and swung upward in a horizontal position above the carriage when required for use, but by which, also, the said carriage-top may readily be adjusted and held at any suitable elevation in any horizontal or inclined position in order to protect the occupant of the 15 carriage from the sun's rays under any angle of declination.

In the accompanying drawings, Figure 1 represents a side view of my improved brace extended in position to support a carriage-top 20 horizontal at its highest elevation. Fig. 2 is a side view of the same, partly folded and in position to support the carriage-top at a less elevation, either horizontal or inclined. Fig. 3 is a perspective outline of a part of an ordinary baby-carriage as heretofore constructed, showing the top in the two positions of raised and lowered.

Like letters of reference indicate like parts. The brace is made preferably of malleable 25 cast-iron; and it consists of four main parts—namely, two bracket-plates, A B, adapted to be secured respectively to the sides of the body and top of the carriage, and two brace-arms, C D, pivoted together at c, at about the 30 middle of the brace, the lower end of the arm C being pivoted at a to the lower bracket-plate, A, and the upper end of the arm D being pivoted at b to the upper bracket-plate, B, as shown in the drawings. That portion of the 35 bracket-plates A and B and of one of the arms C or D to which are fastened the respective pivots a b c is made circular in shape around the respective pivot as the center, and is provided concentrically with a circular row of 40 grooves, sockets, or notches, a' b' c'. A spring, E, riveted with its upper end to the arm C,

has on its lower end a catch, pin, or other projection, e, which engages with the depressions a', being forced and held into the said depressions by the elasticity of the said spring. 55 To the arm D are riveted two similar springs, F and G, (preferably made in one piece, as shown in the drawings,) having similar end projections, f and g, engaging with the depressions c' and b', respectively. 60

Instead of the depressions a' c' b', projections may be used, and the springs E F G may have corresponding depressions instead of the projections e f g. The springs are strong enough to retain the catches in the notches, and thus 65 keep the carriage-top in its adjusted position under ordinary circumstances.

To change the position of the carriage-top it is only necessary to turn the plate B or the 70 arms C D on their respective pivots with application of sufficient power to spring the catches out of their respective notches until they engage with some other notches in the series corresponding to the desired elevation and inclination of the carriage-top. 75

A glance at the drawings will make plain the whole construction and operation. Fig. 2 shows the brace about half folded, the folding shortening the distance between the lower and the upper pivots, a and b, and consequently 80 lowering the carriage-top, (indicated by the line x x.) The carriage-top may be inclined backward or forward at any desired angle—for instance, as indicated by the dotted lines x' x', by simply turning the bracket-plate B a 85 little on its pivot, as indicated by the dotted position corresponding to that of the dotted line x' x' in Fig. 2. One of the arms C D is preferably bent at that end with which it is pivoted to the other arm, as shown, in order 90 to locate the pivot c so far outside the edge of the main portion of the thus bent arm that when the brace is folded the adjacent edges of the two arms will join snugly in continuous contact. 95

In infants' carriages as generally made (see Fig. 3) the top H is connected to the body I by a rigid brace, h, having but one joint, i, which allows of turning it only from the vertical position shown in full lines to that shown 100 in dotted lines.

Having thus described my invention, what

I claim as new, and desire to secure by Letters Patent, is—

1. An adjustable brace for infants' carriages, consisting of the body-bracket A, the arms C 5 and D, and the top bracket, B, pivoted together successively and held in position by spring-catches, substantially as specified.

2. A carriage-brace consisting of the bracket-plates A B and arms C D, pivoted together 10 at a c b, substantially as shown and described, the said bracket-plates and one of the said

arms being provided with a series of notches or catches, a' c' b', partly surrounding the said pivots a c b, respectively, and the said arms C D, having springs E F G, provided with catches or notches e f g to interlock with the respective notches or catches a' c' b', for the purpose set forth.

CARL M. FOGELQUIST.
